United States Patent

Des. 238,392

Patented Jan. 6, 1976

238,392

PORTABLE RADIO

George M. Buckler, Dewitt, N.Y., and Ken-ichi Fukunaga, Tokyo, Japan, assignors to General Electric Company, Syracuse, N.Y.

Filed May 17, 1973, Ser. No. 361,221

Term of patent 14 years

Int. Cl. D14—03

U.S. Cl. D56—4 B

FIG.1.

FIG.2.

FIG.3.

FIG. 4.

FIG. 5.

FIG. 6.

FIG. 1 is a top plan view of a portable radio showing our new design;

FIG. 2 is a front elevational view;

FIG. 3 is a rear elevational view;

FIG. 4 is a left side elevational view;

FIG. 5 is a right side elevational view; and

FIG. 6 is a bottom plan view.

Portions of the radio are diagonally lined to indicate transparency and structure which would be seen through the transparent surfaces has been omitted for convenience of illustration.

We claim:

The ornamental design for a portable radio, as shown and described.
